[57] CLAIM

The ornamental design for a beverage can holder for refrigerator, substantially as shown and described.

DESCRIPTION

FIG. 1 is a perspective view of a beverage can holder for refrigerator, showing our new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a perspective view of a beverage can holder for refrigerator, showing a second embodiment of our new design;

FIG. 7 is a top plan view of FIG. 6;

FIG. 8 is a front elevational view of FIG. 6;

FIG. 9 is a right side elevational view of FIG. 6; and

FIG. 10 is a rear elevational view of FIG. 6.
